(57) **CLAIM**

The ornamental design for a light emitting diode, as shown and described.

DESCRIPTION

FIG. 1 shows a front view of the design according to an embodiment of the invention.

FIG. 2 shows a rear view of the design according to the above-mentioned embodiment of the invention.

FIG. 3 shows a top view of the design according to the above-mentioned embodiment of the invention.

FIG. 4 shows a bottom view of the design according to the above-mentioned embodiment of the invention.

FIG. 5 shows a left side view of the design according to the above-mentioned embodiment of the invention.

FIG. 6 shows a right side view of the design according to the above-mentioned embodiment of the invention.

FIG. 7 shows a top perspective view of the design according to the above-mentioned embodiment of the invention.

FIG. 8 shows a bottom perspective view of the design according to the above-mentioned embodiment of the invention; and,

FIG. 9 shows a front view of the design according to the above-mentioned embodiment of the invention, indicating a translucent portion.
